Primary Examiner — Ania Aman(57) **CLAIM**

We claim the ornamental design for a track for traction of a vehicle, as shown and described.

DESCRIPTION

FIG. 1 is a front perspective view of a track for traction of a vehicle showing our new design;

FIG. 2 is a rear perspective view of the track of FIG. 1;

FIG. 3 is a top view of the track of FIG. 1;

FIG. 4 is a bottom view of the track of FIG. 1;

FIG. 5 is a right side elevation view of the track of FIG. 1; and,

FIG. 6 is a left side elevation view of the track of FIG. 1.

The broken line shown in the drawings are for the purpose of illustrating portions of the article and form no part of the claimed design.
